[57] CLAIM

The ornamental design for a chocolate confection, as shown and described.

DESCRIPTION

FIG. 1 is a front elevational view of a chocolate confection showing my new design;

FIG. 2 is a top perspective view thereof;

FIG. 3 is a left side elevational view thereof;

FIG. 4 is a right side elevational view thereof;

FIG. 5 is a top plan view thereof; and

FIG. 6 is a rear elevational view thereof.

The undisclosed bottom plan view thereof is flat and unornamented.

FIG. 1

FIG. 2

FIG. 3

FIG. 4

FIG. 5

FIG. 6
